CLAIM

The ornamental design for an airsoft gun magazine as shown and described.

DESCRIPTION

FIG. 1 is a front elevational view of an airsoft gun magazine showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a top, front and right side perspective view thereof;

FIG. 8 is a top, front and left side perspective view thereof;

FIG. 9 is a top, rear and right side perspective view thereof;

FIG. 10 is an enlarged view of portion 10 in FIG. 8;

FIG. 11 is an enlarged view of portion 11 in FIG. 9; and,

FIG. 12 is an enlarged view of portion 12 in FIG. 9.

The evenly spaced broken lines shown in the drawings depict portions of the airsoft gun magazine that form no part of the claimed design.

The dot-dash-dot broken lines depict boundaries of the detailed enlargement that form no part of the claimed design.

1 Claim, 12 Drawing Sheets
